UNITED STATES PATENT OFFICE.

RENE D. GROVE, OF MIDDLETOWN, PENNSYLVANIA, ASSIGNOR TO PERFORMO-TOY COMPANY, OF MIDDLETOWN, PENNSYLVANIA, A CORPORATION OF DELAWARE.

DESIGN FOR A WHEELED TOY.

Application filed October 20, 1925. Serial No. 15,183. Term of patent 7 years.

To all whom it may concern:

Be it known that I, RENE D. GROVE, a citizen of the United States, residing at Middletown, in the county of Dauphin and State of Pennsylvania, have invented a new, original, and ornamental Design for a Wheeled Toy, of which the following is a specification, reference being had to the accompanying drawing, forming part thereof.

The figure is a perspective view illustrating the invention.

I claim:

The ornamental design for a wheeled toy as shown.

RENE D. GROVE.
